Primary Examiner — George D. Kirschbaum*Assistant Examiner* — Natasha Vujcic(74) *Attorney, Agent, or Firm* — Oliff PLC(57) **CLAIM**

The ornamental design for an evaporator rough-in box, as shown and described.

DESCRIPTION

FIG. 1 is a front, top, left-side perspective view of the evaporator rough-in box;

FIG. 2 is a front elevational view thereof;

FIG. 3 is a top plan view thereof;

FIG. 4 is a right-side elevational view thereof;

FIG. 5 is a left-side elevational view thereof;

FIG. 6 is a rear elevational view thereof;

FIG. 7 is a bottom plan view thereof; and,

FIG. 8 is a front, top, left-side perspective view similar to FIG. 1, but showing one of the brackets in an extended configuration.

The broken lines depict environmental subject matter only and form no part of the claimed design.

1 Claim, 7 Drawing Sheets(56)
